UNITED STATES PATENT OFFICE.

BERNARD H. SKELLY, OF BRIDGEPORT, CONNECTICUT.

LUBRICATOR.

1,269,869.

Specification of Letters Patent. Patented June 18, 1918.

Application filed November 28, 1917. Serial No. 204,442.

To all whom it may concern:

Be it known that I, BERNARD H. SKELLY, a citizen of the United States, residing at the city of Bridgeport, in the county of 5 Fairfield and State of Connecticut, have invented certain new and useful Improvements in Lubricators; and I do declare the following to be a full, clear, and exact description of the invention, such as will enable others skilled in the art to which it 10 appertains to make and use the same.

This invention relates to certain new and useful improvements in a lubricator for forcing oil to a plurality of bearings and 15 is particularly applicable for supplying the lubricant to the various bearings of an automobile.

Primarily, the invention resides in an improved lubricating apparatus for effecting 20 an expeditious and thorough lubrication of all the bearings and joints to which it is connected to thereby avoid the usual nuisance and inconvenience of soiling the hands and clothing as well as the great waste of 25 both time and lubricant which are incidental to the old manual method of lubricating the bearings independently of one another.

Further, the invention is found in the following features of construction, and the arrangements and combinations of parts hereinafter described in detail and claimed in a succinct manner, reference being had to the accompanying drawing wherein,

Figure 1 is a top plan view of the improved lubricating apparatus;

Fig. 2 is a vertical transverse section thereof on line 2—2 of Fig. 1;

Fig. 3 is a horizontal section on line 3—3 of Fig. 2; and

Fig. 4 is a longitudinal, vertical section taken on line 4—4 of Fig. 2.

Referring more in detail to the drawings, the numeral 1 designates a box-like casing opened at its top for the insertion of the 45 several parts of the pump mechanism including the cylinder block or body which is substantially T-shaped in section to provide a web part 2, that rests on the bottom of the casing, and overhanging and oppositely extending wing parts 3 that serve as 50 sustaining spacers for the side walls of the casing as well as space the web part from

said side walls. This arrangement and construction provides a lubricant chamber 4 which extends from side to side around the 55 ends of the body by reason of the latter terminating short of the end walls of the casing.

This block or body is bored through its top to form spaced series of vertical cylinders 5 from the bottoms of which bored extensions 6 and 7 are made to provide vertically spaced seats 8 and 9 for the inwardly opening ball valves 10 and 11. Through the opposite sides of the web part 2 bores 12 65 are made for establishing communication between the chamber 4 and the respective passage 7. These passages 12 open through the sides of the web part beneath the overhanging wings 3 so that the inlets are practically housed thereby.

Extending laterally from the bottom of each cylinder and into the adjacent wing part 3 is an outlet passage 13 and communicating with this passage is a vertical passage 14 opening through the top of the body, said vertical passage comprising a series of counterbores for providing the vertically spaced seats 15 and 16 for the ball valves 17 75 and 18. Threaded in the upper end of passage 14 is a delivery pipe 19 extending upwardly within the casing and having its upper end deflected through and secured to the side walls of the casing. Thus, means are provided on each side for securely locking 80 the cylinder block in the casing.

The plungers 20 are preferably headed to afford greater bearing surface for the plunger-depressing cams 21 and 22, said plungers being retained against the cams by 90 means of the coil springs 23 which encircle the plungers and bear upwardly on the heads of the latter. The upper end of the cylinder is flared to receive a packing gland 24 which is held in place by the ring 25 on 95 which the lower end of the spring 23 seats.

Pillow blocks or bearings 26 are provided at opposite ends of the body and in these are journaled the shafts 27 which fixedly carry the cams 21 and 22. These shafts also 100 fixedly carry the intermeshing gears 28 and one shaft is extended through the end wall of the casing to receive any desired power-applying means such as a crank handle 29.

In practical use, the lubricating mechanism or apparatus is installed in any convenient position on the automobile and the several delivery pipes connected through piping to the several bearings of the machine. The lubricant having been poured into the chamber 4 at either end opening between the body and casing, the crank handle is turned to rotate the cams in which connection it will be noted that one cam is advanced substantially 180° over the companion cam for effecting alternate depressions of the plungers of both series at relatively timed intervals. As the lubricant is drawn in on the upstroke of the plunger, the ball valves 10 and 11 unseat while the valves 17 and 18 close, this action being reversed on depression of the plungers. Consequently, one or two turns of the crank handle will be effective in supplying sufficient lubricant to each bearing to which a delivery pipe leads.

Thus, may be accomplished in a fraction of a minute that which would require one-half hour or more under the ordinary method of manually oiling each bearing separately beside avoiding all the inconvenience of soiling the hands and clothing and the waste of oil.

The chamber 4 being annular or continuous, a perfect circulation of the lubricant is obtained. All of the passages and cylinders in the body are capable of being bored, the outer end of passage 13 being suitably plugged in an obvious manner.

What is claimed is:

1. In a force feed lubricator, a box-like casing opened at its top, a substantially T-sectioned body disposed therein and formed with spaced series of cylinders opening through its top, each cylinder having a valved inlet extending downwardly and opening laterally through the web of the body and a valved outlet extending laterally in the adjacent overhanging portion of the body and opening upwardly through its top, a delivery pipe threaded in the outlet of each cylinder and passing through the side of the casing, a plunger in each cylinder, the latter flaring at its upper end, a packing gland in the flared upper end of the cylinder about its plunger, a spring encircling the latter and seating on the gland for lifting the plunger, and means for depressing the plungers.

2. In a force feed lubricator, a box-like casing opened at its top, a substantially T-sectioned body disposed therein and formed with spaced series of cylinders opening through its top, each cylinder having a valved inlet extending downwardly and opening laterally through the web of the body and a valved outlet extending laterally in the adjacent overhanging portion of

the body and opening upwardly through its top, spring-lifted plungers in the cylinders, and means for depressing the plungers.

3. In a force feed lubricator, a box-like casing opened at its top, a substantially T-sectioned body disposed therein and formed with spaced series of cylinders opening through its top, each cylinder having a valved inlet extending downwardly and opening laterally through the web of the body and a valved outlet extending laterally in the adjacent overhanging portion of the body and opening upwardly through its top, a delivery pipe threaded in the outlet of each cylinder and passing through the side of the casing, a plunger in each cylinder, and intergeared means for operating the series of plungers.

4. In a force feed lubricator, a box-like casing opened at its top, a substantially T-sectioned body disposed therein and formed with spaced series of cylinders opening through its top, each cylinder having a valved inlet extending downwardly and opening laterally through the web of the body and a valved outlet extending laterally in the adjacent overhanging portion of the body and opening upwardly through its top, a delivery pipe threaded in the outlet of each cylinder and passing through the side of the casing, a plunger in each cylinder, the latter flaring at its upper end, a packing gland in the flared upper end of the cylinder about its plunger, a spring encircling the latter and seating on the gland for lifting the plunger, and a cam for each series of plungers geared to the companion cam for depressing the respective plungers.

5. In a force feed lubricator, a casing, a body arranged therein to provide a continuous lubricant chamber, said body having overhanging lateral portions spaced above the bottom of the casing and provided with a series of vertical cylinders having valved inlets communicating with the chamber, a spring retracted plunger in each cylinder, and means for operating the plungers.

6. In a force feed lubricator, a casing, a body arranged therein to provide a continuous lubricant chamber, said body having overhanging lateral portions spaced above the bottom of the casing and provided with a spaced series of cylinders having valved inlets communicating with the chamber, a plunger in each cylinder, a rotatable cam over each series of plungers for operating the same, and intermeshing gears connecting the cams.

7. In a force feed lubricator, a body having a plurality of cylinders opening through its top, a pillow block arranged at each end on top of the body, each cylinder having a valved outlet also opening through the top of the body and between the pillow blocks and a valved inlet opening through the bot-

tom of said body, plungers operable in the cylinders and extending upwardly between said pillow blocks, and means journaled on the latter for operating the plungers.

5. 8. In a force feed lubricator, a cylinder block, a spaced series of cylinders formed therein, plungers operable in said cylinders, means for operating the plungers, a casing

having a lubricant reservoir at the bottom in which casing the foregoing parts are disposed, valved inlets for said cylinders communicating with said reservoir, a valved outlet for each cylinder, and a delivery pipe leading from each outlet. 10

In testimony whereof I affix my signature. 15

BERNARD H. SKELLY.
